CLAIM

(21) Appl. No.: **29/288,819**

The ornamental design for an ergonomic pressure calibration pump, as shown and described.

(22) Filed: **Jun. 25, 2007**

DESCRIPTION

(51) **LOC (8) Cl.** 15-02

This pump incorporates easy to use handles, a vernier knob to adjust pressure, and inside the vernier knob is the pressure relief valve which relieves the pressure created. The created pressure, is used in conjunction with a sensor to be tested, and a pressure calibrator. The reservoir is a shatterproof, transparent, tapered container which makes viewing the liquid used for pressurization easier to see.
